DUSTER

Filed Jan. 16, 1923

UNITED STATES PATENT OFFICE.

JOHN H. MOORE, OF HUNTINGTON, WEST VIRGINIA.

DUSTER.

Application filed January 16, 1923. Serial No. 612,959.

This invention relates to dusters and the art of making them but more specifically it relates to that form of duster in which the interior part of the dust members is attached to and over a knob on the end of the handle and bent down and secured in place by outer dust members bound to the handle adjacent the interior brush members and the art of making such dusters.

10 In the accompanying drawing, Figure 1 is a side view of my duster completed and ready for use.

Figure 2 is a view of the duster end of the handle showing the knob thereon around and 15 to which the duster materials are attached.

Figure 3 is a view of that part of the handle shown in Figure 2 showing the first stage in the construction of the duster.

Figure 4 is a view of the brush showing 20 the duster material attached to the knob bent over the knob and the outer layer of the material being applied to the handle.

Figure 5 is a fragmentary view of the fabric strip or fibre which is to be attached 25 directly to the knob of the handle.

Figure 6 is a fragmentary view of the slotted fabric strip used in forming the outer part of the duster.

In the drawing the handle as a whole is 30 designated by the numeral 1. On the outer end of the handle is a ring member 2 attached by any suitable means and used for supporting or carrying the duster about. On the inner or duster end of the handle 35 there is formed a knob 3 over and to which the duster elements are to be attached. The duster itself is composed of two parts, an inner one secured over the knob and an outer one secured to the handle adjacent the knob 40 and completely enveloping the first part. The inner part of the duster is composed of strips 4 which have their central part securely bound over the end of the knob by

means of cord or strings 5. The strips 4 are shown to be made of fabric material but 45 may be of any other suitable material. After the strips 4 have been securely attached to the knob end of the handle as shown in Figure 3 the ends of the strips 4 are brought over the knob to form the inner 50 part of the duster. After the brush has reached this stage of construction the piece of fabric such as shown in Figure 6 is wrapped around the duster as already constructed and securely attached to the handle 55 adjacent the knob by means of a cord 9. The fabric piece 6 before being attached to the handle is cut into strips 8 by means of slits 7. These slits extend all the way from one edge of the strip to within a short distance of the other edge leaving a part on one edge of the strip by which all of the strips 8 are held together. It is the unslit part of the strip 6 that is attached to the handle. After the fabric piece 6 has been 60 secured to the handle as above described there is wound around the handle part of the strip 6 and the adjacent handle a cord which forms a binding means such as that shown by the numeral 10 in Figure 1. The duster 70 element as a whole is indicated by the numeral 11.

Having thus described my invention, what I consider as new and wish to protect by Letters Patent, is:

In a duster, a handle having a knob on the end thereof, strips of fabric material secured at their middle part over the end of the knob and having their free ends bent away from the handle to form the inner part 80 of the duster, and a piece of slotted fabric material wrapped around the handle and secured adjacent the knob, the slotted ends forming the outer part of the duster.

In testimony whereof I affix my signature.
JOHN H. MOORE.
